UNITED STATES PATENT OFFICE.

FRANK J. MATCHETTE, OF MILWAUKEE, WISCONSIN, ASSIGNOR TO THE SERVIDOR COMPANY, OF WILMINGTON, DELAWARE, A CORPORATION OF DELAWARE.

VENTILATOR.

Application filed September 18, 1916. Serial No. 120,599.

To all whom it may concern:

Be it known that I, FRANK J. MATCHETTE, a citizen of the United States, residing at Milwaukee, in the county of Milwaukee and 5 State of Wisconsin, have invented a certain new and useful Improvement in Ventilators (Case 8), of which the following is a full, clear, concise, and exact description, reference being had to the accompanying drawings, forming a part of this specification.

My invention relates to ventilators.

The specific embodiments which I have illustrated in the accompanying drawing shows the invention as employed in connection with the service cabinet described and claimed in my copending application, Serial No. 844,622, filed June 12, 1914. It is to be understood, however, that I do not intend to limit the invention for use in this connection only, as the invention is applicable to either inside or outside doors or walls of a room and other means than a service cabinet may be employed in connection with the ventilator.

25 My invention provides a concealed and indirect ventilator for rooms, particularly in hotels, clubs and the like. Suitable means are also provided for controlling the passage of air thru the ventilator. The joint 30 and combined use of the ventilator with the service cabinet or the like provides a device of the utmost simplicity at practically negligible additional expense:

In the accompanying drawing, Figure 1 is 35 a front elevation of the room side of a door embodying my invention.

Figure 2 is the front elevation of a modified form of construction.

Figure 3 is a top plan view of the device 40 shown in Figure 1.

Figure 4 is a vertical section taken on the line 4, 4, of Figure 3.

Figure 5 is an isometric view of the grating forming part of the ventilator.

45 Figure 6 is a similar view of the register or damper forming a part of the same.

Figure 7 is a view similar to Figure 4 showing a modification of the damper mechanism.

50 Figure 8 is a section taken on the line 8, 8 of Figure 7.

Figure 9 is a right end elevation, with parts broken away, of a modification.

Figure 10 is a section taken on the line 55 10, 10, of Figure 9.

Figure 11 is a detailed section taken on the line 11, 11 of Figure 10.

Figure 12 is a top plan view of the modification shown in Figure 2.

Figure 13 is a vertical longitudinal section 60 taken on the line 13, 13 of Figure 12.

Figure 14 is a detailed sectional view showing a modification of the damper in the ventilator.

Figures 15 and 16 are detailed sectional 65 views illustrating modifications in the shape of the ventilator passage.

Figure 17 is an isometric view of the spacing block for the damper of Figure 6.

Figure 18 is a diagram of the controlling 70 mechanism for operating the damper in the embodiment of Figures 2, 12 and 13.

In the embodiment shown in Figures 1, 3, 4, 5 and 6, the door 1 which may be employed in any suitable door frame and which 75 preferably is the door to a room in an hotel or the like, is provided with a cabinet which is preferably of the general type disclosed in my above mentioned application and which is supported between the hanging stile 80 3 and the lock stile 4 which are suitably secured together by means of a top rail 5 and a bottom rail 6.

The cabinet 2 comprises an upper and a lower compartment, the upper compartment 85 being provided with suitable doors 7 upon each side thereof and the lower compartment being provided with suitable doors 8 upon each side thereof.

The main door is equipped with the usual hinges 9 and suitable locking means 10 of any preferred type.

The doors 7 which are upon opposite sides of the cabinet 2 are suitably interlocked as described in the above mentioned application, in order to maintain a barrier between 90 the inside and the outside of the main door 1 while the cabinet 2 is employed for the transmission of articles from or to the room.

The interlock for the doors 7 is controlled by suitable manual operating means 11 and 95 100 is provided with a suitable indicator 12 indicating the order in which the doors are to be operated. The lower doors 8 are also provided with lock operating means 13 and indicating means 14 for the same purpose.

The cabinet 2 comprises a pair of vertical jamb members 15 and 16 which are secured to the lock stile and hanging stile respectively.

The upper and lower parts of the frame which connect the vertical jamb mem- 110

bers 15 and 16 comprise the inner top member 17 and the inner bottom member 18, which complete the lateral walls of the cabinet 2. The inner top and bottom jamb pieces 17 and 18 have their ends secured to the vertical jamb members 15 and 16, but are spaced from the top and bottom rails 5 and 6 respectively.

Top and bottom cheek pieces 19 and 20 respectively are grooved as shown at 21 and 22 to receive suitable tongues formed upon the inner jamb members 17 and 18.

The cheek pieces 19 and 20 extend beyond the inner jamb members 17 and 18 toward the top and bottom rails 5 and 6 of the main door respectively. It is thus seen that an open channel from the outside of the main door 1 thru the space between the jamb members 17 and 18 and the rail members 5 and 6 is provided. The jamb members 17 and 18 have been gained or cut away as shown at 23 and 24 to increase the clearance space between them and the rail members.

The side edges of the cabinet 2 are finished off by vertical cheek pieces 26 and 27, which are suitably grooved as shown at 28 to receive tongues formed upon the vertical jamb members 15 and 16.

In order to control the air thru the above mentioned passages I provide suitable controlling means, the condition of which is displayed by a suitable indicator. To this end upper and lower grille members 29 and 30 are mounted by means of tongues and grooves between the free ends of the cheek pieces 19 at the top of the cabinet and the corresponding pieces 20 at the bottom of the cabinet. This grille member as is shown in Figure 5 is provided with a number of openings 31 for permitting the movement of air thru the ventilator passage. Corresponding damper members 33 and 34 are held by means of guide blocks 35 and 36 just back of the grille members 29 and 30. The damper member 33 comprises a number of vanes or wings 37 which are adapted to close off partially or completely the openings 31 in the grille member 29. Suitable handles or pins 39 and 40 are connected to the damper members 33 and 34 respectively for moving these members to the open or closed position as may be desired. Back of the handles 39 and 40 are placed indicating plates 41 and 42 which have upon their faces suitable legends for indicating the open or closed position of the corresponding damper members. The joint between the vertical jamb members 15 and 16 with the respective stiles 4 and 3 are concealed by suitable moldings 43 and 44, which are continued just around the top and bottom corners as is shown at 45 and 46 in Figure 1.

The grille members 29 and 30 are grooved as shown at 45 and 46 and narrow strips 47 and 48 forming tongues are adapted to en-

ter said grooves and form a closure between the grille members and the corresponding rail members. The narrow tongues 47 and 48 are substantially the same width as moldings 43 and 44 in a vertical direction, but due to their reduced thickness they do not interfere with the openings 31 in the grille members. A particularly important function is performed by the grooves and tongues just indicated in that they prevent any possibility of light shining thru the joint between the grille members and the corresponding rail members.

The interior of the cabinet 2 may be made to communicate with one of the ventilating passages as by means of the apertures 49 shown in Figure 4 and indicated in dotted line in Figure 3.

It can be seen that the modification just described comprises essentially a wall, in this case the door 1, and a rectangular frame or jamb in which one or more of the jamb members are spaced away from the aperture in the wall in order to form a passage between one side of the wall and the other.

In Figures 7 and 8 I have illustrated a modification in which the damper member is operated from the side of the casing instead of above or below. In this structure the cabinet 2 comprises the vertical jamb members 51 which correspond to the jamb members 15 and 16 in the previous modification and the upper and lower horizontal jamb members 52 and 53 which are spaced away from the upper and lower rails 5 and 6 respectively, as is indicated in Figures 7 and 8. The upper and lower cheek pieces 19 and 20 respectively conceal the opening between the rails and the horizontal jamb members and define a U shaped ventilating passage. The upper ventilating passage 54 is controlled by a swinging damper 56 which is mounted upon a horizontal rod 57, having a suitable handle or thumb piece 58 at its outer right hand end as viewed from the room side of the door. The rod 57 is provided with means for applying sufficient friction to hold the damper 56 in the desired position. For this purpose a U shaped clip of sheet metal 60 is held with its limbs against the rod 57 by means of the screw 61 which holds it with the desired degree of firmness. The lower ventilating passage 55 is provided with similar damper means 62 mounted upon a rod 63 having a handle 64 and held by a suitable friction clamp 65. Bearing plates 67 for the rods 57 and 63 are provided upon the outer face of the cabinet and suitable legends, such as indicated at 68 at the lower left hand corner of Figure 7, may be provided for informing the operator of the condition of the corresponding damper.

Suitable moldings 69 lie along the junction between the cabinet 2 and the stiles of the door 1. At the top and bottom the

moulding 69 is placed directly in line with the outer end of the cheek pieces 19 and 20 in order to give the door a uniform, finished appearance.

5 In the structure illustrated in Figures 9, 10 and 11 the two dampers 56 and 62 for controlling the upper and lower ventilating passages respectively are connected to a common operating handle 70, which handle 10 is connected by means of rods 71 and 72 lying in the corner under the moulding 73 which is cut away as is shown in Figure 11 to accommodate the same. The rod 71 is bent over and connected by means of a 15 link 74 to the damper 56 so that as the handle 70 is raised or lowered it will raise or lower the damper 56. The damper of the lower passage-way is connected thru a short link 75 to a rocking lever 76, the other end 20 of which is connected to the rod 72. It can be seen that as the operating handle 70 is raised to its upper position, the dampers 56 and 62 will be closed and thereby will shut off the ventilating passages 54 and 55. 25 A suitable indicating plate 77 is mounted on the stile member back of the handle 70 and is provided with suitable legends which are adapted to lie back of the handle 70 to indicate the position of the damper members 30 in the ventilating passages.

In Figures 2, 12, 13 and 18, I have indicated a simplified structure in which the cheek pieces are dispensed with and the doors alone form the side walls of the cabinet 2. The stiles and rails of the main door 1 are substantially the same as shown in connection with Figure 1. Suitable locking means 10 and hinges 9 are also provided. The cabinet 2 comprises an upper and a 40 lower compartment, the upper compartment being closed upon each side by suitable doors 7, which in the form shown are curved to give the entire cabinet a generally oval cross section, as is indicated in Figure 12. The 45 main frame of the cabinet is formed of the vertical jamb members 78 and 79 and the upper and lower jamb members 80 and 81, which are spaced away from the respective rail members 5 and 6 to form suitable ventilating passages 82 and 83.

It will be noted that the ends of the horizontal jamb members 80 and 81 are provided with tenons 84 which are set into mortises formed upon the inner side walls 55 of the vertical jamb members 78 and 79. A central partition member 85 which divides the cabinet into the upper and lower compartments is also secured to the side jamb members by means of the tenon and mortise 60 construction described. It will be noted that the partition member 85 lies in such a position as to be overlapped by the adjacent edge of each of the doors. This type of construction provides a very simple but 65 artistic article. It will be noted that the

rail members 5 and 6 project slightly into the ventilating passages 82 and 83 in order to prevent an intruder from seeing thru the ventilating passage when the adjacent door is open. In order to shut off any possibility 70 of light thru the ventilating passage when one of the doors are opened, the rail members may be set into the ventilating passage so far that even when the adjacent door is opened no direct rays of light can pass between the adjacent jamb members 80 or 81 and the rail members 5 or 6.

Suitable dampers 86 and 87 are provided for the ventilating passages 82 and 83 and these dampers, which are mounted upon 80 suitable rods 88 and 89, are adapted to be operated in common by suitable push buttons or controlling devices 90, which are provided with suitable legends as is indicated in Figure 2, to indicate the position of the 85 damper members.

In Figure 18 the operating connections for the dampers 86 and 87 are shown. The push buttons 90 are connected to the ends of a rocking arm 91 which in turn is connected by a shaft 92 to a second rocking arm 93. The rocking arm 93 lies inside the cabinet 2. The arm 93 is connected by operating rods 94 and 95 to the dampers 86 and 87. 90

It is to be understood that the form of 95 the ventilating passage is not to be confined or limited to the rectangular channel shown in previous figures, as channels of the shape shown in Figures 15 and 16 may be employed instead. In Figure 15 the ventilating passage-way 90 is cut into the jamb member 91 and a suitable coaming 92 is provided for binding or finishing the lower edge of the rail 5. 100

In Figure 16 substantially the same construction has been shown except that the coaming 92 has been reduced in size to form merely a moulding or finishing piece upon the bottom edge of the rail 5, while in Figure 15 this piece 92 is wide enough to lie 110 flush with the edges of the moulding 93. 105

It is apparent that the damper may be pivoted about its center instead of at one side, so that the mounting rod may be at the center as is shown in Figure 14. 115

In the different modifications illustrated there is the dominant feature of the main wall, in this case the door 1, with a transverse frame or casing formed of the various jamb members above referred to, which 120 frame or casing lies in an aperture in the main wall, but has at least one wall of the casing or frame spaced away from the edge of the aperture and has side walls which overlap the aperture so as to form an indirect ventilating passage between opposite sides of the main wall. In addition, each form shows a suitable controlling damper for controlling the passage of air thru this 125 ventilating passage. 130

I do not intend to limit the invention to the forms, dimensions nor proportions shown and do not intend to limit the invention to any of the details of construction except 5 as the same appear in the appended claims.

I claim:

1. In combination a main wall or septum, a rectangular frame or casing supported in 10 said wall with a space between said casing and main wall, said frame being substantially deeper than the thickness of said main wall and having front and rear walls on the opposite sides of said main wall, said front and rear walls forming closing means for 15 for said frame or casing and projecting over the space between said frame and the main wall to form an indirect passage between the opposite sides of the main wall.

2. In combination a main wall or septum, 20 a rectangular frame or casing supported in said wall, said frame or casing being substantially deeper than the thickness of said main wall and having front and rear walls on opposite sides of said main wall and secured to said frame or casing and having an end wall spaced from said main wall, 25 said front and rear walls forming closing means for said frame or casing and projecting over the space between said frame or 30 casing and the main wall to form an indirect passage between opposite sides of said main wall, and a damper concealed in and controlling said passage.

3. In combination a main wall or septum, 35 a rectangular frame or casing supported in said wall, said frame or casing being substantially deeper than the thickness of said main wall and having front and rear walls on opposite sides of said main wall and secured to said frame or casing and having an end wall spaced from said main wall, 40 said front and rear walls forming closing means for said frame or casing and projecting over the space between said frame or 45 casing and the main wall to form an indirect passage between opposite sides of said main wall, a damper concealed in and controlling said passage, and indicating means for indicating the position of said damper.

50 4. In combination a main wall or septum, having an aperture therethrough, a casing or frame supported in fixed position in said aperture and comprising a plurality of members lying with their flat sides at right angles to the plane of the wall, and being of 55 substantially greater width than the thickness of the wall, said members forming a closed figure, one of said members being supported at its ends away from the adjacent 60 edge of the aperture, side walls for closing off both sides of said casing, said side walls overlapping on each side the space between the main wall and the casing, thereby concealing said space and forming an indirect 65 ventilating passage.

5. In combination a main wall or septum having an aperture therethrough, a casing or frame supported in fixed position in said aperture comprising a plurality of members of substantially greater width than the 70 thickness of the wall lying with their flat sides at right angles to the plane of the wall, said members forming a closed figure, one of said members being supported at its 75 ends away from the adjacent edge of the aperture, side walls for closing off both sides of said casing, said side walls overlapping on each side the space between the main wall and the casing, thereby concealing said space and forming an indirect ventilating 80 passage, and a movable damper concealed in said passage for controlling the movement of air thru said ventilating passage.

6. In combination a door comprising rails and stiles, a transverse frame secured to said door in stationary position, said frame comprising members of substantially greater width than the thickness of the door lying at right angles to the rails and stiles, said frame being secured to the stiles of the door 90 but being spaced away from one of said rails to provide a ventilating passage between said frame and the corresponding rail, and side walls for closing off both sides of said transverse frame, said side walls covering over and concealing said space, said side walls being spaced away from said rails whereby a ventilating passage is formed between the corresponding rail, the side walls 95 and the transverse frame. 100

7. In combination a door comprising rail members and stile members, a transverse frame secured to said door in fixed position, said frame comprising members of substantially greater width than the thickness of the door lying at right angles to the rail and stile members, said frame being permanently secured to the stile members of the door, but being spaced away from both of said rail members to provide a ventilating 105 passage above and below said transverse frame and side walls for closing off both sides of said transverse frame, said side walls overlapping the space between the rails and the frame to form an indirect ventilating 110 passage. 115

8. In combination a door comprising rail members and stile members, a transverse frame secured to said door in fixed position, said frame comprising members of substantially greater width than the thickness of the door lying at right angles to the rail and stile members, said frame being secured 120 permanently to the stile members of the door, but being spaced away from both of said rail members to provide a ventilating passage above and below said transverse frame and side walls for closing off both sides of said transverse frame, said side walls overlapping the space between the rails and 125 130

the frame to form an indirect ventilating passage, and damper members for each of said ventilating passages said damper members being concealed in said passages.

- 5 9. In combination a door comprising rail members and stile members, a transverse frame rigidly secured to said door, said frame comprising members of substantially greater width than the thickness of the door
- 10 lying at right angles to the rail and stile members, said frame being secured to the stile members of the door, but being spaced away from both of said rail members to provide a passage above and below said trans-
- 15 verse frame and side walls for closing off both sides of said transverse frame, said side walls overlapping the space between the rails and the frame to form an indirect ventilating passage, and damper members for
- 20 each of said ventilating passages concealed in said passages, a common controlling mem-

ber and connections between said handle and said dampers for permitting both dampers to be adjusted by said common member.

10. In combination a main door, a cabinet 25 within said door, said cabinet projecting from opposite sides thereof, said cabinet comprising a transverse frame or casing, said casing having one of its walls spaced away from the door to form a ventilating 30 passage and side walls for closing off both sides of said casing, said side walls overlapping the space between the casing and the door, said cabinet having an opening thru said casing to permit communication be- 35 tween the interior of the cabinet and said ventilating passage to permit ventilation of the inside of the cabinet.

In witness whereof, I hereunto subscribe my name this 12th day of September, A. D. 40 1916.

FRANK J. MATCHETTE.
